AUTOMATICALLY ADJUSTABLE C CLAMP

William J. Malecki, New York, N. Y.

Application February 19, 1949, Serial No. 77,329

3 Claims. (Cl. 144—305)

1

The present invention relates to new and useful improvements in clamps.

More particularly, the present invention proposes a novel quick-release screw-clamp, and the aim is to provide a novel and valuable such clamp and one of outstanding utility when in the form of a so-called C-clamp and hence illustrated herein in connection with a C-clamp; the present invention being characterized by a marked simplicity of construction and ruggedness throughout, thereby to give a dependably long life, and at the same time characterized by a superior means for manual actuation instantaneously to free the screw from meshing relation of its thread with the thread of a nut.

A further feature of the invention is that while a spring means, one which preferably is a one-piece single unit, is employed, for normally holding the screw to said meshing relation, merely a single simple manual thrust is required to overcome the pressure of the spring means and thereby temporarily throw the nut thread out of engagement with the screw thread, that is, merely a single manipulable part has to be handled, by depressing the same, to effect this break-of-engagement result.

Another feature of the invention is the provision of a combination of parts such that when said manipulable part is depressed, the two jaws of the clamp thereby are wholly freed for straight endwise and parallel movement toward and away from each other, without impediment of any kind.

Another object of the present invention proposes a novel arrangement for preventing the jaws from becoming released while the clamp is in use in a manner to retain the clamp against being accidentally released.

A still further object of the invention proposes slidably mounting the threaded nut in a tunnel-like enlargement which is open along one side in a manner to facilitate formation of the enlargement and the mounting of the threaded nut therein.

It is a further object of the present invention to construct a clamp of the type described which is simple and durable and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

2

Fig. 1 is a side elevational view of a clamp constructed in accordance with the present invention.

Fig. 2 is an enlarged fragmentary vertical sectional view taken substantially on the line 2—2 of Fig. 1.

Fig. 3 is a fragmentary horizontal sectional view taken substantially on the line 3—3 of Fig. 2.

Fig. 4 is a fragmentary vertical sectional view taken substantially on the line 4—4 of Fig. 2.

Fig. 5 is a view similar to Fig. 1, but showing the clamp constructed in accordance with a modification of the present invention.

Fig. 6 is an enlarged fragmentary vertical sectional view taken substantially on the line 6—6 of Fig. 5.

Fig. 7 is a fragmentary horizontal sectional view taken on the line 7—7 of Fig. 6.

Fig. 8 is a top perspective view of a slide member, per se, used in the form of the invention shown in Figs. 5 to 7.

Fig. 9 is a bottom plan view of the slide member, per se.

Fig. 10 is a side elevational view of the backing piece, per se, used in the form of the invention shown in Figs. 5 to 9.

Fig. 11 is a top plan view of the backing piece, per se.

Fig. 12 is a view similar to Fig. 5, but illustrating the clamp constructed in accordance with a still further modification of the present invention.

Fig. 13 is an enlarged partial front elevational view looking in the direction of the line 13—13 of Fig. 12.

Fig. 14 is a partial vertical sectional view taken on the line 14—14 of Fig. 13.

The clamp, illustrated in the first form of the invention shown in Figs. 1 to 4, includes a screw 10 carried by the main C-shaped body 11 having a fixed jaw 11a.

The already mentioned slide member is as a whole marked 12. This member 12 is accommodated in a tunnelled enlargement 14 integral with the clamp's main body 11, such tunnel affording a slideway 15 for the member 12. Said member 12 has a fairly large opening 16 therethrough, this opening extending from a rounded end wall 17 of the member 12. The end wall 17 has its inner side threaded forming a half-nut 18 facing the opposite plane end wall 19 of the member 12. The wall 19 has a step-down 20.

The step-down or undercut 20 affords a conventional means for mounting the butt end of a leaf-spring 21, as by use of a single attaching screw 22. The spring 21 is a simple leaf-

spring, and it has been found that the same should be shaped, for optimum action in normally holding the parts as shown in Fig. 2, that is, for normally maintaining the nut and screw in mesh, substantially as shown in that view.

At 23 is indicated the movable jaw of the clamp, this jaw being rockably and rotatably movable within adequate limits, by inclusion of the conventional ball and socket connection 24. A screw handle 25 is provided at the free end of the screw 10 for turning the same.

Means is provided on the member 12 to retain it against accidental sliding movement while the clamp is in use. The retaining means comprises a shoulder 19^a, see Fig. 2, formed on the end wall 19 of the member, opposed to the end wall provided with the spring 21, for engaging the adjacent wall of the enlargement 14. The screw 10 has sliding engagement through the walls of the enlargement 14, and when the jaws 11^a and 23 are clamped against the opposite sides of a piece of work 50, as indicated by the dot and dash lines in Figs. 1 and 2, the screw 10 will slide through the enlargement 14 until the member 12 engages the top wall of the enlargement, as shown in Fig. 2. In this position, the shoulder 19^a will be engaged with the end of the enlargement 14 and prevent accidental inward movement of the member 12 while the clamp is in use. To free the member 12, several turns of the screw 10 are required moving the member 12 away from the wall of the enlargement 14 until the shoulder 19^a moves clear of the end of the enlargement after which the member 12 is free to be urged inward against the action of the spring 21.

Operation

The screw 10 ordinarily may be spirally advanced toward or retracted away from the fixed clamp jaw 11^a, as usual, by turning the handle 25. When, however, rapid rectilinear and hence non-rotative movement of the jaw 23 is desired, as in the many cases familiar to those well acquainted with the clamp art, instantaneously this may be temporarily allowed for, merely by thumb thrust against the end of the member 12 at its spring-carrying wall 19, thereby to force the member 12 downward and then inward the slight distance required to disengage the thread of the nut from the screw. This tensions the spring 21, so that when said thumb pressure is relieved, immediately the nut snaps back into operative engagement with the nut.

Referring to the modification of the present invention illustrated in Figs. 5-11, wherein the parts to which are applied reference numerals with primes added correspond, respectively, to the parts to which have been applied the same reference numerals but without primes, two features are here specially shown. One of these features is the use of an expandable coil spring instead of a leaf-spring as in Figs. 1-4, thereby desirably calling for a somewhat different structural design for the slide member 12'; and the other of these features is a slanting of the slideway 15', desirably accompanied by a corresponding inclination of the enlargement 14', relative to the axis of the screw, thereby to obtain a particularly fortuitous action, not only when the nut and screw are disengaged, but also when they are reengaged.

Considering first in detail the slide member 12', this perhaps being shown best in Figs. 8 and 9, it will be noted that extended from the

rounded end wall 17' and laterally beyond the groove and land elements of the half nut 18', the slide member 12' incorporates a pair of thin like side walls 26, 26, these merging at their forward ends into the plane end wall 19', which wall 19' has an L-extension floor portion 27. In lieu of the step-down 28, the member 12' has a step-down 28 which, extended across the top of the wall 19' and extended partially along the tops of the two walls 26, is U-shaped in top plan. The already mentioned plate or block, to be welded or otherwise suitably attached to the main body of the member 12', to complete the latter, is shown at 29, after the already mentioned coil spring 31 is inserted. A lug 30 for centering one end of said spring is carried by the wall 19', and said spring, designated 31, extends toward a backing piece 32 carrying a spring-end engaging boss 32^a.

As will be noted best from Figs. 10 and 11, the piece 32 has an uninterrupted vertically straight end horizontally concavely curvilinear face, for fitting against the turns of the land of the screw 10', has parallel vertical sides and is of a width about equal to the perpendicular spacing between the walls 26, and has laterally rounded upper and lower ends; all whereby the spring 31 is always held to ideal action, without chance of entanglement of an end portion thereof with the screw thread.

To guide the sliding movements of the backing piece 32, the vertical sides thereof have trunnions 32^b extending laterally therefrom, which trunnions 32^b are slidably extended into complementary elongated slots 26^a formed in the side walls 26 of the member 12'.

By virtue of the slant of the slideway 15', it has been discovered, the already mentioned optimum action, both in disengaging and reengaging the screw and nut, is had. In this connection it should be appreciated that while the thread of the screw is shown in all the views in the conventional manner, that is, for instance, in Fig. 6, as though the said thread side elevationally of the screw has rectilinear upper and lower boundaries; as a matter of fact such thread at top and bottom would have a sinuous curvature as thus viewed. In other words, each turn of said thread, at the side of the screw to the left in Fig. 6 and toward the there remote part of the screw, incorporates a helically extending downward fall-off curvature. Due to this fact, the slant of the slideway 15' in the direction indicated in Fig. 6 is now believed to be preferable, and may be proved to be essential, in attaining said optimum action. It has been found by test that with the slideway thus inclined, disengagement of the nut from the screw is particularly easy and instantaneous; while reengagement of these parts is similar. It has been noted that on such reengagement, that is, snap back of the member 12' on releasing manual pressure thereon, the same is accompanied by a distinct clicking sound and a slight rocking of the member 12' about a horizontal axis intermediate its ends; and this rocking is allowed for, as shown in Fig. 6, by putting a slight taper along the top of said member 12'.

It is to be understood that the features just described may be employed when a leaf spring is used, as for instance, the leaf spring 21, instead of such a coil spring as that shown at 31.

In the further modification of the invention shown in Figs. 12 to 14, the clamp closely resembles that shown in Figs. 5 to 11. However, in

this form of the invention, the side of the enlargement 14", opposed to the side from which the C-shaped body 11' extends is open. This facilitates the formation of the slideway 15' for the member 12" and further facilitates the engagement of the member 12" in the slideway 15'. Also, the member 12" occupies the full space between the top and bottom walls of the enlargement 14" forming the slideway and the member 12" has no shoulder (see 19a' in Fig. 6) for restraining the member 12" against accidental movement while the clamp is in use.

In other respects this latter form of the invention is similar to that shown in Figs. 5 to 11 and similar reference numerals are used to identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An article of the class described comprising a main body including a hollow enlarged end piece, hollow slide means retained for sliding movement in said end piece and including half nut threads on its interior surface, a clamp screw rotatably received in said hollow end piece and adapted to engage said half nut threads, said

slide being loosely retained in the hollow end piece to permit a limited movement thereof in an axial direction of said clamp screw, tension means on said slide and urging said half nut threads laterally into normal engagement with said clamp screw, and a shoulder on said slide engaging said end piece upon a slight axial movement of said slide to prevent accidental inward movement of said slide when the clamp is in use.

10 2. The combination of claim 1 wherein said slide is undercut at a side thereof and said tension means is a leaf spring secured to the undercut of the slide.

15 3. The combination of claim 1 wherein said shoulder extends above the upper surface of the outer end of the slide so that it normally is positioned against the exterior edge of said enlarged end piece.

WILLIAM J. MALECKI.
